JOHN T. DAWSON, OF FROSTBURG, MARYLAND.

Letters Patent No. 63,708, dated April 9, 1867.

IMPROVEMENT IN CHURNS.

The Schedule referred to in these Letters Patent and making part of the same.

TO ALL WHOM IT MAY CONCERN:

Be it known that I, JOHN T. DAWSON, of Frostburg, in Alleghany county, and State of Maryland, have invented a new and useful Improvement in "Churns;" and I do hereby declare that the following is a full, clear, and exact description thereof, reference being had to the accompanying drawing, through letters of reference marked thereon, forming part of this specification, in which—

Figure 1 represents a vertical section of my churn; all the interior and operating parts being in elevation.

Figure 2 is a horizontal section of the same, taken on the line xx of fig. 1.

The same letters appearing on both figures indicate corresponding parts.

My invention consists in a novel and peculiar conformation of the revolving dasher in combination with a square or rectangular tub or box, whereby an upward and inward motion is given to the cream, causing considerable agitation with comparatively little labor; also, in combination with such devices, of a dish or pan supported above the dasher in which the butter as it is formed is collected and separated from the buttermilk.

To enable others to make and use my invention, I will proceed to describe it by referring to the drawing, in which—

A represents the vessel in which the cream to be churned is deposited, and which I make preferably of rectangular form, as in that form no ribs or vanes are necessary to cause the deflection of the fluid towards the centre of the vessel. This effect may, however, be produced by constructing a round vessel with vertical ribs, vanes, or corrugations, but all irregularities in the interior of such vessels render it more difficult to keep them clean, hence the preference is given to the rectangular vessel. In the centre of this vessel is arranged a vertical shaft, B, fitted to revolve in a step, c , in the centre of the bottom of the vessel A. To the lower end of this shaft is attached the dasher D, which revolves with said shaft, and will be further described hereinafter. Above the dasher is a pan or dish, E, supported on an adjustable collar, G, on the shaft, the whole being enclosed with a cover, H. Above the cover, attached to a portion thereof, is adapted a frame, I, which supports a bevel-wheel, J, and pinion K, for rotating the dasher shaft B, which are operated by means of a hand-crank, L; or in any other suitable manner. The pinion K is provided with a square extension, a , of its axis or shaft, which fits loosely into a corresponding mortise in the upper end of the shaft B, so that when it is desired to open or uncover the churn, the gearing will lift off without having to withdraw any keys or screws. The dasher D consists of four blades, more or less, which are of what is commonly known as the double ogee form. The concave or advance side in the course of its rotation is bevelled off upwardly in its central portion, gradually assuming a vertical face towards its extremity and its junction with the axis or shaft B, as more clearly represented in red lines in fig. 2. The action of this dasher in its rotation is evident will be to lift the cream and throw it against the sides of the vessel, which, being angular, will deflect it upwards and towards the centre into the pan E, which being provided with a number of holes, e , will allow it to pass downward to be again agitated in like manner, and as the butter is formed it will all be thrown up and lodged in said pan, leaving nothing to obstruct the action of the dasher on the unchanged cream and buttermilk, which is thus effectually caused to yield the last particle of butter possible to be obtained from it.

In operating this churn, the pan E should be so arranged that the upper edge of its rim should be about level with the top of the cream in the vessel A, which may be regulated by raising or lowering the collar G on the shaft B, which latter is provided with a series of holes, one above another, for the insertion of the pin c' , which supports said collar. This collar G is made semicircular in its cross-section on the upper side, so as to present as small a friction surface as possible to the under side of the pan, which will, when first started, and the cream is perfectly fluid, rotate with the axis around which it is supported, but as soon as the butter begins to form, and it becomes more and more loaded therewith, it will gradually cease to move, until the shaft B will rotate within, leaving it stationary or nearly so.

Having thus described my invention, what I claim as new, and desire to secure by Letters Patent, is—

1. The revolving dasher D, constructed substantially as described, and operating in combination with the rectangular vessel or its equivalent essentially as set forth.

2. The pan E, arranged and operating in combination with the dasher D, substantially as specified.

In testimony whereof I have hereunto set my hand this 14th day of February, 1867.

JOHN T. DAWSON.
